UNITED STATES PATENT OFFICE

EDWARD F. GEIGER, OF BINGHAMTON, NEW YORK

CARBURETOR

Application filed June 25, 1928. Serial No. 287,908.

This invention relates to improvements in carburetors and has for its object the provision of improved means for controlling the quality of the fuel mixture.

5 Provision is made for controlling the fuel quality through the commonly used operating range primarily by the speed of the engine and secondarily by the degree of throttle opening so that at low engine speeds 10 at any throttle opening the fuel mixture will be relatively rich and at high engine speeds with partially closed throttle conditions the mixture will be relatively lean and with widely open throttle conditions at high engine 15 speeds the mixture will be of medium rich quality.

The present invention has for its object the provision of novel means for securing the aforesaid fuel mixture quality.

20 A further object of the present invention resides in the provision of a novel means for exerting a variable resistance to the action of a controlling valve in accordance with the operating conditions of the engine.

25 In the drawing:

The figure 1 shows substantially a central vertical sectional view of my improved carburetor.

In more detail the carburetor comprises 30 the usual well known parts such as a manifold connection or outlet conduit 1 having associated therewith a mixture conduit 2 provided with a throttle valve 3 operated in the usual manner. There is also a Venturi section 4, 35 disposed at the entrance of the mixture conduit 2; an air inlet 5 provided with a conventional choke valve 6 operated in the usual manner and a constant level float chamber 7 which is supplied with fuel through pipe 8.

40 A fuel nozzle 9 extends into the constricted portion of venturi 4 and is supplied with fuel from the constant level reservoir 7 by means of passages 10, 11, 12 and 13. To control the flow of fuel to the nozzle 9 a needle 45 valve 14 is provided. A tube 15 open to the atmosphere at its lower end extends into fuel nozzle 9 and serves to conduct air to the upper end of the latter which air assists in atomizing the fuel when the carburetor is in 50 operation. Disposed at an intermediate point

between the Venturi section 4 and the air inlet conduct 5 is an air valve 16 yieldingly moved towards its closed position by a spring 17 and having a stem or guide member 18 which extends up and slidably fits in a cylindrical bore 55 19 of the carburetor body. This cylindrical bore 19 is connected at its upper end with the mixture conduit 2 by means of a passage 20 which extends into the mixture conduit at a point adjacent the throttle valve 3 and at a 60 point on the Venturi side thereof when the said throttle valve is in nearly closed position. A needle valve 20a is provided to limit the effective opening of passage 20. An auxiliary duct 21 is also provided between the 65 upper end of the cylindrical bore 19 and the mixture conduit. Such auxiliary passage or duct enters the mixture conduit at a point somewhat nearer the venturi than the point of entrance of passage 20. In order to prevent the air valve 16 from entirely closing an adjustable stop member 22 is provided.

In the operation of the carburetor, the pumping action of the associated engine produces a depression of pressure in mixture 70 conduit 2 which causes the air to flow through air inlet 5 past valve 16 and through the venturi 4. This depression of pressure also causes fuel to flow from the float chamber past the needle valve 14, through passages 12, 11 and 75 10 and out of nozzle 9 into the venturi 4 where it becomes commingled with the air flowing therethrough to thereby form the fuel mixture required to operate the engine.

The quality of the fuel mixtures is modified 80 to meet the requirements of the engine at various speeds and power outputs by means of the air valve 16, which by offering resistance to the flow of air from the air inlet 5 to the venturi 4 produces a greater depression 85 of pressure in the venturi than would otherwise normally maintain there for any given air speed. Such increase of depression of pressure in the venturi produces a corresponding increase in the flow of fuel from the 90 nozzle 9 with a consequent enrichment of the fuel mixture. The disposition of passage 20 with respect to the throttle valve 3 is such that when the latter is opened somewhat, for example to the position marked 3a, the depres- 95 100

sion in pressure existing in the mixture conduit 2 upon the engine side of the throttle is effective to reduce the pressure in chamber or bore 19. In such bore the upper part of 18 5 acts as a piston or plunger and is drawn upwardly by the depression of pressure in 19 so that this action tends to and pulls up valve 16 against the action of the spring 17 and thus tends to reduce the resistance offered by the 10 air valve 16 to the flow of air to the venturi. The ultimate action is that the depression of pressure in the venturi is proportionately reduced whereby the amount of fuel entering the air stream is proportionately reduced. 15 It may be also stated that the depression of pressure above the throttle 3 is greater than that below it. Accordingly, this pressure difference is available to bring about action of the piston 18.

20 As the engine speed increases the depression of pressure upon the engine side of the throttle valve 3 increases, thereby increasing the depression of pressure in bore 19 and further lessening the effect of valve 16 to produce an enrichment of the fuel mixture. At 25 high engine speeds, the depression of pressure on the engine side of throttle valve 3 may become great enough to pull the valve 16 entirely up. Under such conditions the valve 30 16 will offer no resistance to the flow of air to the venturi and the amount of fuel fed into the air stream will depend entirely upon the normal depression of pressure caused by the action of the venturi and by the setting 35 of the fuel needle valve 14. This needle valve may be set to furnish a very lean mixture if desired under the last mentioned operating conditions.

The object of the auxiliary passage 21 is to 40 somewhat modify and lessen the effect of passage 20 upon the piston-like stem of valve 16 so that the latter functions more in accordance with the speed of the engine than would be the case if passage 20 alone were 45 provided. The depression in pressure on the engine side of the throttle valve 3 reaches its greater value under nearly closed throttle conditions and even at slow engine speeds under these conditions this depression of 50 pressure may be greater than that which maintains at high engine speeds under intermediate open throttle conditions. The auxiliary passage 21 tends to compensate for the 55 above noted variation in pressures by allowing air to flow into bore 19 through the passage 21 when the throttle valve is in a nearly closed position such as 3a, thereby lessening the effect of passage 20 under this condition.

When the throttle valve 3 is in a nearly 60 closed position such as 3a, air will flow from the fuel mixture conduit 2 on the Venturi side of the throttle through auxiliary passage 21 into bore 19 and out of the latter through passage 20 into the fuel mixture conduit 2 on the engine side of the throttle

valve. The needle valve 20a may be adjusted to limit the rate at which air can flow out of bore 19 and through 20 and therefore, it can be used as a means for adjusting the total effective depression in pressure in the bore 19 and thus afford a means for regulating the action of valve 16 in modifying the quality of fuel mixture.

When the throttle valve is in an intermediate open position such as 3b, the depression in pressure in the fuel mixture conduit 2 upon the engine side of the throttle is comparatively less even at high engine speeds than obtains under nearly closed throttle conditions. However, at such intermediate open 75 throttle positions both passage 20 and auxiliary passage 21 are subject to the depression of pressure upon the engine side of the throttle and such depression of pressure is communicated unrelieved to bore 19.

80 From the foregoing it will be understood that the throttle in accordance with its relative position with respect to 20 and 21 will modify the ultimate suction which is available to act upon 18. Higher suction effects 85 are cut down when the throttle is in nearly closed positions and in relatively wider open positions the full suction effects are available without diminution.

90 The part 18 which is in the form of a plunger may be provided with slight clearance if desired to allow some air to flow along 95 it into bore 19 and in this way the action may be additionally varied. Various amounts of clearance may be provided as desired.

100 It will be understood that at slow engine speeds under medium open and open throttle conditions the suction conditions are such that there is comparatively little depression of pressure in bore 19 and accordingly under these conditions there is a relatively small supplementary pull upon the stem 18 so that the valve 16 acts in normal manner to enrich the mixture.

105 In accordance with the present invention 110 the means for varying the action of the air valve 16 is one which is disposed between the outlet conduit and the valve 16 itself. This means takes into account the pressure conditions adjacent the throttle 3 and it is in accordance with these conditions that the action of enriching air valve is modified.

115 What I claim is:

120 1. A carburetor with a throttle, a venturi, an air resisting valve disposed in the intake of the venturi, and provided with resilient means to resist opening movement thereof, in combination with means for modifying the action of said valve, said means comprising 125 means brought into action by the depression of pressure which exists adjacent the throttle valve for effecting modification of the action of the air valve said means being shut off by the throttle when the latter moves to closed position.

2. A carburetor having a throttle, a venturi and an air valve disposed in the inlet to the venturi and having yielding means to resist opening movement thereof, in combination with a plunger connected to said valve, and ducts extending to a point adjacent the throttle to exert suction effects upon the said plunger to thereby modify the action of the air valve in accordance with the pressure conditions adjacent the throttle, said means being shut off by the throttle when the latter moves to closed position.

3. A carburetor having a controlling air valve with yielding means to resist opening movement thereof which air valve varies the degree of enrichment of the fuel mixture, an outlet conduit provided with a throttle, a venturi the aforesaid controlling air valve being disposed in the air inlet to the venturi, means for supplying fuel to the venturi, and means intermediate the outlet conduit and said air valve for utilizing the suction effects in the conduit adjacent the edge of the throttle for modifying the action of the mixture enriching air valve.

4. The invention set forth in claim 3 in which the means intermediate the outlet conduit and air valve comprises a plurality of ducts which variably cooperate with the throttle to modify the available suction effects in the conduit which are employed for controlling and modifying the action of the air valve.

5. A carburetor with an outlet conduit, a throttle valve, a venturi, an air controlling valve for modifying the richness of fuel mixture by controlling the intake to the venturi, resilient means for controlling the aforesaid valve, means for supplying fuel to the venturi, a chamber connected to the outlet conduit by passages which extend adjacent to the edge of the throttle in said conduit, both of said passages being disposed upon the venturi side of the throttle when the latter is in closed position and means in said chamber operatively connected to the air valve for modifying its action in accordance with pressure variations in said chamber.

6. In a carburetor having a venturi, means for supplying fuel thereto, an outlet conduit therefrom, a throttle valve therein, and an air flow resisting valve in the inlet to the venturi for varying the degree of enrichment of the fuel mixture, and means including a passage to the outlet conduit and brought into operation under the control of the suction conditions which exist above the throttle at high engine speeds for changing the resistance of said air valve whereby enrichment of the fuel mixture under these conditions is prevented said passage being shut off by said throttle when the latter is in closed position.

7. A carburetor having a venturi, a mixture outlet therefrom, an air valve in the inlet to the venturi, means comprising mov-

able elements operatively connected to the said air valve, and dual ducts to the mixture outlet to apply related pressures to said movable elements derived from the mixture outlet to thereby modify the action of the air valve.

In testimony whereof I hereto affix my signature.

EDWARD F. GEIGER.
